INVENTOR.
HARRY F. ROLLER.

BY *A. B. Bowman*
ATTORNEY

UNITED STATES PATENT OFFICE.

HARRY F. ROLLER, OF SAN DIEGO, CALIFORNIA.

VALVE AND CAP APPARATUS.

Application filed January 13, 1922. Serial No. 528,896.

To all whom it may concern:

Be it known that I, HARRY F. ROLLER, a citizen of the United States, residing at San Diego, in the county of San Diego and State of California, have invented a certain new and useful Valve and Cap Apparatus, of which the following is a specification.

My invention relates to a valve and cap apparatus, more particularly to an apparatus for holding the valve of a pneumatic tube open as desired to permit the air to pass out and the like, and the objects of my invention are: first, to provide an apparatus of this class which will hold the valve open for emptying a tube thus providing a time saving apparatus; second, to provide an apparatus of this class which may be readily applied; third, to provide an apparatus of this class which is positive and efficient in its action; fourth, to provide an apparatus of this class which is made a part of a valve and cap of the pneumatic tube now in use; fifth, to provide a novelly constructed valve and cap apparatus, and sixth, to provide an apparatus of this class which is very simple and economical of construction, durable, easy to install and which will not readily deteriorate or get out of order.

With these and other objects in view as will appear hereinafter my invention consists of certain novel features of construction, combination and arrangement of parts and portions as will be hereinafter described in detail and particularly set forth in the appended claims reference being had to the accompanying drawings and to the characters of reference thereon which form a part of this application in which:

Figure 1 is a sectional elevational view through the middle of the conventional valve stem with the valve and cap in position for use; Fig. 2 is another sectional and elevational view through the middle of the valve stem and valve, and showing the cap reversed and in position to hold the valve open; Fig. 3 is a sectional and elevational view through 3-3 of Fig. 2; Fig. 4 is an enlarged fragmentary side view of the cap and valve showing the special features of each; Fig. 5 is an end view taken at 5-5 of Fig. 4; and Fig. 6 is an end view taken at 6-6 of Fig. 4.

Similar characters of reference refer to similar parts and portions throughout the several views of the drawings.

The valve casing 1, retainer plug 2, valve seat member 3, valve member 4, valve stem

5, spring seat 6, spring 7 and cap 8 constitute the principal parts and portions of my structure.

The valve casing 1 is of the conventional type secured to the pneumatic tube. The plug 2 is provided with external threads 2^a which engage and are held in position by the internal threads 1^a of the valve casing 1. Mounted concentrically and reciprocably at the inner end of the retainer plug 2 is the valve seat 3. Said valve seat is provided with a packing 3^a to prevent air or other fluids passing by the valve seat. The valve 4 is secured to the valve stem 5 which is reciprocably mounted on and guided by the retainer plug 2 and the spring seat 6 and is retained in position therein by the flattened portions 5^a and 5^b thereon. The valve member 4 is held in engagement with the valve seat 3 by the spring 7 which is interposed between and held in position by the shoulder 4^a of the valve member 4 and the spring seat 6 which spring seat bears against the shoulders 1^b of the valve casing 1. The retainer plug 2 is provided with two oppositely disposed L-shaped lugs 2^b facing in opposite directions adapted to engage similar lugs 8^a on the reduced portion 2^b of the cap 8. It will be noted that the engaging surfaces of the L-shaped lugs 2^b are beveled at 2^c as shown to provide for their interlocking. The slot 8^b of the cap 8 is adapted to receive the lug 2^b of the retainer plug 2 and serves as a wrench to tighten or release said retainer plug. A recess 8^c is provided in the cap 8 to make clearance for the portion 5^b of a valve stem that extends beyond the valve casing.

It is obvious that by reversing the cap 8 in the manner shown in Figs. 2 and 3 of the drawings and permitting the L-shaped lug 8^a of said cap to engage the lugs 2^b of the retainer plug 2, the valve stem 5 is forced inwardly against the compression of the spring 7. Since the valve member 4 is secured to the valve stem 5, it is obvious that the said valve is disengaged from its seat 3 permitting the gases or fluids to escape by the valve.

It is further obvious that since the spring 7 is under compression the valve stem 5 is forced against the cap 8 thus keeping said cap in engagement with the retainer plug 2 by the L-shaped lugs 8^a and 2^b respectively and that they interlock by reason of the beveled portions 2^c.

Though I have shown and described a particular construction, combination and arrangement of parts and portions I do not wish to be limited to this particular construction, combination and arrangement but desire to include in the scope of my invention the construction, combination and arrangement substantially as set forth in the appended claims.

10 Having thus described my invention what I claim as new and desire to secure by Letters Patent is:

1. In an apparatus of the class described, a supporting means provided with a locking lug portion, a valve provided with a stem reciprocally mounted therein, and a depressor member adapted to engage with and depress the valve stem and provided with lugs thereon adapted to interlock with said locking lug portion on said valve supporting means.

2. In an apparatus of the class described, a supporting means provided with locking lug portions, a valve supported therein, and a depressor member adapted to engage with and depress said valve and provided with lugs thereon adapted to interlock with said lug portions on said valve supporting means when said valve is shifted in its supporting means.

3. In an apparatus of the class described, a supporting means provided with a locking lug portion, a valve provided with a stem reciprocally mounted therein, and a cap adapted to engage with and depress the valve stem and provided with lugs adapted

to interlock with said locking lug portion on said valve supporting means.

4. An apparatus of the class described, including a casing, a valve seat member mounted therein, a plug mounted in said casing positioning said valve seat and provided with locking lugs, a valve engaging said valve seat member and secured to a valve stem reciprocably mounted in said casing, a cap adapted to bear against said valve stem and disengage said valve from said valve seat, and provided with lugs adapted to engage and interlock with said lugs on said plug when said valve is disengaged from said valve seat.

5. A valve and valve cap apparatus, including a supporting means provided with a locking portion, a valve reciprocally mounted therein, and a cap member adapted to engage with and depress said valve and provided with locking means adapted to interlock with the locking portion of said supporting means when said valve is depressed.

6. A valve apparatus, including a supporting means provided with a locking portion, a valve reciprocally mounted therein, and another member provided with a locking portion, said member adapted to engage said valve and depress the same and interlock with the locking portion of said supporting means.

In testimony whereof, I have hereunto set my hand at San Diego, California, this 6th day of January, 1922.

HARRY F. ROLLER.
